TOILET ARTICLE

Nathan A. Hallwood, Columbus, Ohio, assignor
of one-half to W. S. Cewan, Columbus, Ohio

Application July 10, 1934, Serial No. 734,525

6 Claims. (Cl. 132—85)

This invention relates to toilet articles and more particularly to a combination comb and brush. An object of the invention is to provide an article of this character wherein hair combing and brushing operations may be performed simultaneously.

Another object of the invention is to provide an article of this kind which is intended primarily to be carried in a pocket formed in the clothes of 10 the user, and which is so formed that it will take up appreciably no more room in the pocket than an ordinary comb.

It is also an object, in one form of the invention, to arrange the bristles of the brushing elements of the article on each side of the comb so that they will lie in a direction pointing towards the operating end of the comb, and to extend the bristles a slight distance below the inner root 20 ends of the teeth so that when the comb is used in the ordinary manner at an angle to the scalp, the nearest bristles will be brought into brushing engagement with the hair.

In another specific form of the invention, the brushing elements are mounted on a frame pivoted 25 at its ends to the comb body and which frame may be swung to one side or the other of said body, depending upon the side of the comb used nearest the head, or to a position in alignment with the teeth of the comb so that said brushing 30 elements and comb will lie substantially in the same plane and thereby presents an article of substantially no greater cross-sectional area than the comb body by itself.

With these and other objects in view, which 35 will appear as the description proceeds, the invention consists in the novel features of construction, combinations of elements and arrangement of parts hereinafter to be more fully described and pointed out in the appended claims.

40 In the accompanying drawing:

Fig. 1 is a side elevation of the toilet article formed in the shape of a comb and including the brushing elements which together with the comb forms the present invention;

45 Fig. 2 is a vertical transverse sectional view taken on the line II—II of Fig. 1;

Fig. 3 is a side elevation disclosing a modified form of the invention;

Fig. 4 is a transverse vertical sectional view 50 taken on the line IV—IV of Fig. 3;

Fig. 5 is a similar view showing the brushing element swung to either side of the comb body;

Fig. 6 is a detail side elevation of a comb 55 wherein the bristle elements are detachably carried by the comb body;

Fig. 7 is a transverse sectional view on the line VII—VII of Fig. 6.

Referring more particularly to the drawing, the numeral 1 designates the toilet article in its entirety which has the general contour and size 5 of an ordinary pocket comb. In the form disclosed in Figs. 1 and 2, the back 2 of the comb is provided near its lower edge with brushing elements 3 formed of bristles and located on each side of the comb body, as disclosed more particularly in Fig. 2. These bristles may be attached to the back 2 by molding the same therein or by any other suitable manner. The bristles are so positioned as to lie in a direction pointing towards the lower outer ends of the teeth 10 4 and terminate at a point slightly below the root ends of said teeth, that is, where the teeth join the comb body.

It will be noted that the bristles are pointing 15 downwardly and slightly outwardly so that when the comb is used in an ordinary manner at an angle to the scalp, said bristles will be positioned substantially perpendicular thereto and thereby produce a brushing action upon the hair. In cross section, the comb converges toward the 20 lower end of the teeth in advance of the bristles, which will cause the bristles on one side of the comb to engage the hair while the bristles on the other side will be raised to a position above the hair. However, as both sides of the comb are 25 identical, either side thereof may be used with a similar effect.

30 By this arrangement, the bristles are permitted to lie flat on each side of the comb body and thereby take up little or no more room than an ordinary comb, thus facilitating the insertion and withdrawal of the comb in connection with a pocket or containing case. The comb may be handled in an ordinary manner as the bristles do not interfere with the fingers in the normal 35 grasping of the comb. Further, by the positioning of the bristles below the thickest portion of the back 2, the latter will serve to protect the bristles from injury during the handling thereof.

40 In the modified form of the invention disclosed in Figs. 3 to 5, inclusive, the comb body 5 is provided with a swinging brushing element 6 which consists of a frame bar 7 having embedded 45 therein and pointing downwardly therefrom bristles 8 all closely arranged, on the order of 50 a brush. The bar has its ends provided with up-standing arms 9 which are positioned within recesses 10 formed in the ends of the comb body 5 when in an inactive position disclosed in Figs. 3 and 4. Connected to the ends of the bar 7 and 55

the upper ends of the arms 9 are links 11 which are pivotally connected at their opposite ends as at 12 to the outer members 13 formed with the ends of the body 5, and which links also occupy 5 the recesses 10 when the brushing element is in alignment with the teeth of the comb.

By the provision of the links 11, the brushing element 6 may be swung to either side of the comb body as illustrated in Fig. 5 and be so positioned that the bristles will be directed downwardly or in the same direction as the teeth of the comb. The outward or upward movement of the brushing element 6 is limited by the connections 14 joining the outer members 13 with 15 the comb body 5. The bars 7 are of sufficient length to space the brushing elements 6 a sufficient distance from the comb body so as to permit the fingers of the user to be entered therebetween, and thereby be capable of being manipulated 20 in the usual way with the brushing element following the comb as it is pushed through the hair. This article may be conveniently positioned within the pocket of the user by first swinging the frame or brushing element 6 to a 25 position in alignment with the teeth 15 in which position the brushing element will add slightly to the width of the comb but will be within the distance representing the thickness thereof.

In the form of my invention disclosed in Figs. 30 6 and 7, an ordinary comb is indicated at 17, the same being formed with a longitudinally extending back 18 and integral teeth 19. The bristle element is associated with a comb of this type by being provided with a metallic or other form of 35 35 a resilient body 20 from the opposite and lower ends of which project outwardly diverging rows of bristles 21. By this construction, the bristle element may be slidably engaged or disengaged with the comb proper and facility obtained both 40 in the manufacture and use of the article.

From the foregoing, it will be seen that a toilet article has been provided wherein is combined in connection with an ordinary comb construction, a brushing element which is so arranged with 45 respect to the teeth of the comb that it will follow the passage of the comb teeth through the hair thereby effecting the combing and brushing of the hair all in one operation which customarily requires two separate operations. The brushing 50 elements are so arranged as to take up little or no more room than the body portion of the comb and can therefore be readily used as a pocket article and be conveniently carried around. The device or article is extremely simple 55 in its construction and is not apt to become out of order with continued use. The device may also be made of materials commonly employed for forming articles of this kind.

Although I have shown and described what I 60 consider to be the preferred form of construc-

tion, nevertheless it will be understood that slight changes may be made, such as in the proportion of parts and arrangement thereof, without departing from the spirit and scope of the invention as pointed out in the appended claims.

5

What is claimed is:

1. In a toilet article of the class described, a comb body formed with recesses at its ends which are open at their lower ends, a brush carrying frame arranged in connection with said comb body and having its ends pivoted to links occupying said recesses.

10 15 20 25 30 35 40 45 50 55 60

2. In an article of the class described, a comb body, a brushing element including a bar normally arranged in a position below and in alignment with the teeth of said comb body, and means for pivoting said bar to the ends of said comb for permitting the bar to be swung to a position spaced from either side of said comb body.

3. In an article of the class described, a comb body, a brushing element including a bar mounted for swinging movement about an axis parallel to said comb body and normally arranged in a position below and in alignment with the teeth of said comb body, and means formed with said comb body for limiting the upward swinging movement of said bar.

35 40 45 50 55 60

4. An article of the class described comprising a comb body, a brush carrying bar normally arranged below and in alignment with the teeth on said comb body, link means connecting said bar with said comb body in such a way that it may be swung to either side thereof and still have its vertical center line substantially parallel with that of the comb, and means for limiting the swinging movement of said bar when the brushing member is substantially level with the root of the teeth on said comb.

5. An article of the class described comprising a comb body, a brush carrying bar, a pair of links pivotally connected to the ends of the comb body and brush bar and supporting said bar below said comb body, and angular shoulders formed on said comb body for limiting the pivotal movement of said links, said shoulders permitting said brush to swing to a position at least horizontal with the root of said comb.

40 45 50 55 60

6. An article of the class described comprising a comb body, a brush carrying bar normally arranged below and in vertical alignment with the teeth on said comb body, and a pair of depending parallel links arranged at each end of the comb body, the said links being of equal length and disposed in vertically offset relationship, vertically offset horizontally arranged pivots uniting the upper ends of each pair of links to the comb body and vertically offset horizontally arranged pivots uniting the lower ends of each pair of links with said bar.

NATHAN A. HALLWOOD.
